UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,572.

Specification of Letters Patent. Patented Apr. 15, 1919.

Application filed November 27, 1917. Serial No. 204,254.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to stud and socket fasteners.

15 Among the objects of the invention are to provide a socket having resilient jaw means for engagement with the neck of the stud which is simple in construction, reliable in operation, and in which the entrance of 20 the stud into the socket is very easily effected, while retaining those advantages which are inherent to stud and socket fasteners wherein separation of stud and socket can be effected by relative tipping movement 25 in one direction only.

In the drawings:

Figure 1 is a front elevation showing a preferred form of one embodiment of my invention;

30 Fig. 2 is a section thereof, partly in elevation, on the line 2—2 of Fig. 1;

Fig. 3 is a sectional view, partly in elevation, on the line 3—3 of Fig. 2; and

35 Fig. 4 is a section, partly in elevation, on the line 4—4 of Fig. 3.

Referring to the preferred form of my invention selected for illustrative purposes, I have shown a stud 5 having a head 6 and providing a neck 7 for engagement by resilient jaw means typified by the transverse 40 resilient jaws 8 and 9 carried in a socket which preferably, as shown, comprises a front casing 10, and a rear casing 11. The stud 5 may be secured to the curtain 12 of 45 an automobile, or any other suitable object, while the socket may be secured to a second curtain 13, or any other suitable object, preferably a fabric, preferably by prongs 14 projecting from the front plate 10 of the 50 casing and passing through a clench plate 15.

One of the resilient jaws, preferably the lower jaw 9, is preferably free to move in either direction toward or from the aperture 16 in the socket. The other resilient 55 jaw, herein shown as the upper jaw 8, is

preferably supported on one side by an inclined surface 17, which may conveniently be formed in the back plate 11 and which is adapted to oppose movement of the jaw 8 away from the axis of the aperture 16 when 60 the stud is to be withdrawn from the socket, but which is relatively free to move away from said axis when the stud is to be entered in the socket. I preferably space the front plate 10 (Fig. 4) at a sufficient distance from 65 the back plate 11 so that when the spring jaw 8 is pressed forwardly, as is necessarily the case when the stud is entered in the socket, the spring jaw 8 will be moved away from the cam surface 17 and therefore be 70 free to move upwardly, thereby yielding to facilitate entrance of the head of the stud in the socket. When, on the other hand, the stud is to be withdrawn from the socket, the front shoulder of the neck or groove 7 75 presses the jaw 8 firmly against the back plate, in which position the jaw 8 will not move upwardly because of the inclined projection 17.

When the stud is to be removed from the 80 socket, the lower end of the socket may be moved outwardly, which will cause the lower jaw 9 to yield downwardly so that the stud can be rocked about the jaw 8 to permit withdrawal of the stud from the socket by an 85 unbuttoning action.

While I have shown and described one embodiment of my invention, it will be understood that changes involving omission, alteration, substitution and reversal of parts, 90 and even changes in the mode of operation, may be made without departing from the scope of my invention, which is best defined in the following claims.

Claims:

1. A stud and socket fastener comprising, in combination, a stud having a head and a neck, a socket providing a jaw element yieldable when said stud is entered in the socket but substantially unyielding when said stud 100 is withdrawn from said socket.

2. A stud and socket fastener comprising, in combination, a stud having a head and a neck, a socket providing a resilient jaw and a stop element co-operating with said jaw to 105 oppose movement thereof on retraction of said stud from said socket, while permitting said jaw to yield substantially freely when said stud is entered in said socket.

3. A stud and socket fastener comprising, 110

in combination, a stud having a head and a neck, a socket providing a transverse jaw element yieldable when said stud is entered in the socket but substantially unyielding 5 when said stud is withdrawn from said socket.

4. A stud and socket fastener comprising, in combination, a stud having a head and a neck, a socket providing a transverse re- 10 silent jaw and a stop element coöperating with said jaw to oppose movement thereof on retraction of said stud from said socket, while permitting said jaw to yield substantially freely when said stud is entered in said 15 socket.

5. A stud and socket fastener comprising, in combination, a stud providing a head and a neck, a socket providing transverse jaws for engagement with opposite sides of said 20 neck, one of said jaws being freely movable away from said neck, and the other of said jaws having an abutment opposing movement of the latter jaw away from said neck.

6. A stud and socket fastener comprising, in combination, a stud providing a head and a neck, a socket providing transverse jaws for engagement with opposite sides of said neck, one of said jaws being freely movable away from said neck, and the other of said 30 jaws having an abutment opposing movement of the latter jaw away from said neck when said stud is withdrawn from said socket.

7. A stud and socket fastener comprising, in combination, a stud providing a head and a neck, a socket providing transverse jaws 35

for engagement with opposite sides of said neck, one of said jaws being freely movable away from said neck, and the other of said jaws having an abutment opposing movement of the latter jaw away from said neck when said stud is withdrawn from said socket, while permitting substantially free movement of said jaw away from said neck when said stud is entered in said socket. 40

8. A stud and socket fastener comprising, in combination, a stud having a head and a neck, a casing having resilient jaw elements therein for engagement with said neck, said casing having an inclined portion at the rear 50 thereof coöperating with one of said jaws to oppose movement thereof when the stud is withdrawn from the socket, while permitting movement of said jaws when the stud is entered in the socket. 45

9. A stud and socket fastener comprising, in combination, a stud having a head and neck providing between them a shoulder; a socket providing a jaw element yieldable when said stud is entered in the socket but 60 substantially unyieldable when said stud is withdrawn from the socket, and providing a second jaw opposite the first jaw, said second jaw being yieldable when the stud is entered in the socket and when disengaging 65 force is applied to the stud and socket to produce relative tipping movement about the first named jaw as a fulcrum.

In testimony whereof, I have signed my name to this specification.
